DESIGN FOR A HOLDER FOR COCKTAIL OR SODA STIRRERS, PENCILS, OR THE LIKE

Manfred Rosenblatt, Kew Gardens, N. Y.

Application September 27, 1945, Serial No. 122,372

Term of patent 3½ years

(CL. D44—24)

To all whom it may concern:

Be it known that I, Manfred Rosenblatt, a citizen of the United States of America, residing at Kew Gardens, in the county of Queens and State of New York, have invented a new, original, and ornamental Design for a Holder for Cocktail or Soda-Stirrers, Pencils, or the like, of which the following is a specification, reference being had to the accompanying drawing, forming part thereof.

Fig. 1 is a front view of holder for cocktail or soda-stirrers, pencils, or the like showing my new design.

Fig. 2 is perspective view thereof.

Fig. 3 is top view thereof.

I claim:

The ornamental design for a holder for cocktail or soda-stirrers, pencils, or the like, substantially as shown.

MANFRED ROSENBLATT.
